UNITED STATES PATENT OFFICE.

GORDON CAMERON, OF WOLLASTON, MASSACHUSETTS, ASSIGNOR TO SEARS B. CONDIT, JR., OF BOSTON, MASSACHUSETTS.

ELECTRIC SWITCH.

Application filed February 27, 1918. Serial No. 219,379.

To all whom it may concern:

Be it known that I, GORDON CAMERON, a subject of the King of Great Britain, and a resident of Wollaston, county of Norfolk, and State of Massachusetts, have invented an Improvement in Electric Switches, of which the following is a specification.

My invention relates to electric switches adapted for the control of motors or other electric power consuming apparatus or devices, and has particular reference to that type of switch in which the switch contacts are immersed in oil.

An object of my invention is the design of a switch and enclosing case therefor in which the operating parts are completely enclosed, and thereby protected from external influences, and yet which may be readily and easily opened for the inspection of the switch mechanism.

A further object of my invention is the provision of means whereby the removal of cover plate from the switch enclosing case causes a movement of the switch mechanism from a closed to an open position, thereby causing the switch mechanism to be "dead" or disconnected from the line and thereby harmless previous to any possible contact therewith by an operator upon a move to adjust or repair the mechanism.

The means by which I accomplish this object of my invention is the disposition of a member in engagement with cover plate and so arranged that when said cover plate is in position on the enclosing case, the member is moved from operative engagement with the switch mechanism, but upon the removal of the cover plate from the switch enclosing case, said member is permitted to be moved into engagement with the latch, or means restraining the switch in closed position, to cause the disengagement of the latch and the consequent unlocking of the switch members and their removal to open position.

Another object of my invention is to provide means whereby all removable plates or covers of the enclosing case are locked against removal from said case by a predetermined cover plate in its covering position on the case.

The means by which this object of my invention is attained comprises a spring actuated rod normally tending to move from

locking engagement with a cover by its spring, but adapted to be moved and maintained into locking engagement with the cover by the movement of said locking cover into, and the maintenance thereof in closed relation with the switch enclosing case.

Another object of my invention is the provision of a switch whereby the operator is compelled to rapidly move the switch mechanism toward closed position in order to move in such closed position and in which the switch is locked out from such closed position upon an insufficiently rapid movement of the switch mechanism toward closed position.

The means by which I accomplish this object of my invention is the provision of a pivoted latch adapted to engage a projection on the switch handle when said handle is in half-open position, but to be disengaged therefrom during a sufficiently rapid movement of said handle from full open position toward closed position.

Another object of my invention is the construction of a switch, the component parts of which are formed from stamped or drawn sheet metal, whereby the expense of making the switches in quantities is relatively low, and which parts are strong, substantial and durable in operation.

Fig. 1 is an elevation, partly in section, of a switch embodying my invention.

Fig. 2 is a plan view of the switch with top cover removed.

Fig. 3 is a sectional view along the lines 3—3 of Fig. 2.

Fig. 4 is a section taken along lines 4—4 of Fig. 1.

Fig. 5 is a detail of the locking means for the oil receptacle.

Fig. 6 is a detail of the switch operating mechanism in open position.

Fig. 7 is a detail of the latch with cover removed.

Fig. 8 is an enlarged plan view of the latch.

As here shown, the switch includes the supporting or base plate 10, upon which the switch mechanism is disposed. Said base plate 10 is of rectangular form and is arranged at the bottom of the rectangular case or enclosure 11, which is formed with a lower inturned edge or bottom 12 to provide a support therefor, and to which said

base is secured. Said case 11 is adapted to be fixed to a support by suitable supporting means, not necessarily shown.

An oil receptacle 13, formed of drawn metal and of cylindrical form, is secured to the under side of said case, and is adapted to be filled with oil to a depth sufficient to effectively cover the switch contacts depending therein from the base 10. The upper 10 peripheral portion of said oil receptacle 13 is provided with four reflexed strips of sheet metal 14, riveted or otherwise secured thereto. The reflexed ends 15 are outwardly extended and at a slight angle with the 15 axis of the oil can, thereby forming, in effect, portions of screw threads. Said thread members 14 are adapted to be rotated or screwed into engagement with complementary members 16 secured to the inturned 20 edged portion 12 of the case 11, whereby the open end of the oil can is forced and held securely into engagement with the base 10.

A pin 14', secured to the bottom 12 of the case 11, is disposed in the path of movement 25 of said thread portions 14 to limit the rotary movement of the oil container.

The top of said enclosure or case 11, in which is disposed the operating mechanism for the switch members, is formed of two 30 portions, one of which, 17, is permanently secured to the top of said case, and the other of which, 18, is detachably secured thereon. The permanently secured cover portion 17 is formed, at the terminal edge 35 thereof intermediate the end walls of said enclosure, with an upturned edge 19. A strip 20 is riveted to the interior face of said cover portion whereby to form a groove or slot therebetween and the upturned edge 40 19 in which the edge 21 of the detachable cover portion 18 may be disposed when in position on the casing 11. Said cover portions are formed with downwardly bent edges to snugly engage the walls of the enclosure 11, and the more effectively to cover 45 the top opening thereof. The interior surface of the detachable cover portion 18 adjacent the wall of the enclosure or casing, is provided with resilient arm 22, formed with 50 a slot or opening 23 therein, and an inwardly bent end portion.

A pin 24 is secured to the wall of the casing 11 and, in the closed position of the cover 18, is disposed in the opening 23 of 55 said resilient arm 22 thereby locking said cover against unintentional removal from said case.

A button is arranged in the wall of the casing 11, one end of which engages the 60 resilient arm 22, and the other end of which projects through the said wall and is adapted to be pressed inwardly to flex said arm 22 sufficiently to enable the disengagement of the pin 24 with said arm, whereby 65 that end of the cover portion 18 bearing

said arm may be moved upward until the arm clears the top of the enclosure, whereupon the cover portion may be laterally moved from the enclosure and access to the interior thereof obtained.

That portion of the switch mechanism depending from the base 10 into the oil can or receptacle 13 is supported from the frames 25 formed of metal strips bent into substantially rectangular form and secured to the base 10, in spaced relation by rivets passed through the inturned ends 26 thereof. Insulating bars 27 and 28 are secured to said frames 25 in spaced relation by bolts or screws, 29, and form terminal boards 80 or blocks to which the movable and stationary switch contacts and members are secured and from which connection is made to the line or other component parts of the switch.

The ends of the terminal boards 27 and 28 are formed to closely conform to the shape of the oil container 13, whereby said blocks 27 and 28 form guides aiding in the correct positioning of the container to the switch 90 housing. Said blocks also form means preventing the container from being moved into contact with a switch or contact member.

The stationary switch contacts include contact strip 30. The lower ends of said strips are bent at right angles to form contact portions 31 extended beneath said board 27 and said strips are secured to said board in spaced relation by means of bolts 32.

The ends of the contact portions 31 of the strips 30 are provided with slotted auxiliary contacts 33 which are adapted to be engaged by the auxiliary contact members of the movable switch members. Said auxiliary contacts 33 are detachably secured to the contact ends of the strips 30, and are formed with duplicate contact faces whereby, upon the erosion of one face, the contacts may be reversed to present a fresh engaging or contacting face.

The upper ends of the contact strips 30 project through apertures in insulating bushings 34 arranged in the metal base 10, whereby said strips are insulated from said base, and said strips terminate in binding means, 105 as bolts 35, by which connection to the line or circuit to be controlled may be obtained.

The terminal block 28 is arranged to support the movable switch members which are pivoted to lugs secured to said block. Said lugs are formed with a back portion 36, the edges of which are flexed to form the side portions extended into the ears 37 to which the movable switch members are pivoted at 38. A recess is thereby formed between the back 36 of said lugs and the reflexed side portions thereof and conducting strips 39 are disposed therein and clamped between the back of said lugs and the terminal blocks by means of bolts 40 thereby securing said 115 120 125 130

strips and lugs securely to said block and also providing efficient electrical contact between said strips and lugs.

The conducting strips 39, above those portions thereof secured to the terminal board, are twisted at right angles thereto, and extend upwardly through bushings 41 in the base 10. The upper and terminal portions thereof, projecting above the base 10, have secured thereto, by means of bolts 42, conducting leads 43, which form terminals of the overload trip coils hereinafter to be described.

The movable switch members 44 are formed of flat strips and are pivoted at 38 to said lugs depending from the terminal block 28. The end portions of said switch members 44, which are pivoted to said lugs, are twisted, as shown, into a plane at right angles to the major portion of the strip, whereby a large bearing surface is obtained with said lugs. The other ends of said strips 44 are bent or reflexed to form two substantially parallel portions 45 and 46, which 25 form supports for the auxiliary switch contacts 47.

Auxiliary contacts 47 are formed of cylindrical rods slidably disposed in the parallel portions 45 and 46 of said movable switch members 44, and coiled springs 48 are disposed thereon between said parallel portions. Pins 49 are arranged in said contacts and against which said springs act to extend said contacts in the direction of the 35 stationary contacts.

Because of said springs, the auxiliary contacts are adapted to make initial contact with the stationary contact strips at the detachable members 33, and thereafter to yieldingly engage said contacts upon continued movement of the movable switch members to permit the subsequent engagement of the main switch contacts.

The final break between the stationary and movable contacts is also arranged to occur between said auxiliary contacts, and therefore said contacts receive the destructive arc caused by said break or rupture of the circuit. As said contact rods 47 are inexpensive, they may be cheaply renewed when necessary.

Pig tails or flexible leads 50 are secured to the ends of said contact rods 46 by means of screws 51 and the other ends of said leads are clamped between the switch arms 44 and the operating means for said arms.

The main contact, or brush, members 52 are secured to the arms 44 intermediate the ends thereof, by bolts 53 and are adapted to 60 make contact with the contact portions 31 of the contact strips 30. Said brush members are composed of a plurality of flexible leaves, as is common practice.

Bar 54 of an insulating material, such as 65 wood, for instance, is secured to all of said

switch arms 44 intermediate the ends thereof by bolts 53, and forms means insulatingly connecting all of said switch arms for simultaneous movement. The bolts 53 serve to secure in fixed relation to the switch arms 44, the brush members 52, the flexible leads 50 and the main conducting leads 55 which are clamped between said bar 54 and the switch arms 44, the other ends of said latter leads being connected to the terminal board 28 by means of the bolts 40, and by means of which leads connection is made between the movable switch members and the contact strips 39.

The ends of said bar 54 project beyond the end switch arms 44 and stirrup members 56, formed of sheet or strip material, are secured thereto by means of bolts 57. Said strips form means to which the switch operating mechanism is attached, and by means of which the movable switch members are controlled.

The switch operating mechanism includes the shaft 58, journalled in brackets or supports 59 upon the supporting base 10 within the enclosing case 11 and extending substantially across the width of said case.

An arm 60 is secured to one end of said shaft 58, and has a roller 61 pivoted at 61' to the extremity thereof. Said roller is adapted to be engaged by the latch hereinafter to be described to restrain the switch in closed position.

Said arm 60 is formed with a lateral extension 62, the end 62' of which is bent at right angles with the extended portion to form a projection adapted to be engaged by the switch operating handle to move the switch from open position into closed position.

A link 63 is pivoted at 64 to an intermediate part of arm 60, and said link extends through the base 10 to the stirrup 56 of the movable switch member, to which it is pivoted at 65. The end of the operating shaft 58, remote from said arm 60 is provided with an arm 66 arranged in a plane with said arm 60 and has a second link 63, corresponding to the first link 63, pivoted thereto at 67. The other end of said second link 63 is pivoted to the other stirrup. Said links 63 and arms 60 and 66 form means whereby a movement of the operating shaft 58 serves to move the movable switch member between open and closed positions.

The operating shaft 58 extends through and beyond the arm 60 secured thereon and an operating handle 68 is loosely mounted thereon and restrained against removal therefrom by the cotter pin 69.

The side face 70 of the operating handle is adapted to engage the projection 62' of the arm 60 to thereby move said arm 60 in a direction toward switch closed position, and the arrangement is such as to permit

the return of said handle to its normal position independent of said arm 60 and therefore of the operating mechanism.

The operating handle 68 is also formed at 5 its extremity, with an inturned projection 71, which is adapted to engage a part of the latch or switch locking means to cause the disengagement thereof with the roller 61 of the arm 60, to permit a movement of the 10 switch members to open circuit position.

The operating handle 68 projects through the base 10 and inturned edge 12 of the enclosure 11 through a slot provided for that purpose, and a hand engageable portion 72 15 is detachably secured thereto. Said portion 72 of the handle is bent, as shown, to prevent contact of the hand with the oil receptacle 13 in the operation of the switch.

By the provision of a handle constructed 20 in two parts as shown, various forms of handle extremities may be provided to adapt the switch for shipper operation or for connection with a rope, cable or link for remote control.

25 A spring washer 120 is loosely arranged on the operating shaft 58 and between the operating handle 68 and the arm 60 whereby said handle and arm are held in frictional engagement. By this means the handle may 30 remain in a position to indicate the closed condition of the switch instead of falling back to a vertical position as it might otherwise do, and may also be moved toward the right independently of the switch mechanism 35 to cause the tripping of the switch.

Limit stops 79 are secured on base 10 under the arm 60 and 66 and in the paths of movement thereof, and serve to limit the open circuit movement of the switch mechanism.

40 Means are provided whereby the operating handle must be moved toward switch closed position above a certain predetermined speed to arrive at that position, and to thereafter move the switch members into closed position. Said means include a latch 73 disposed above the operating handle and pivoted to the wall of the enclosure 11 at 74.

Said latch 73 is formed with a lower 45 arcuate face 75, which is adapted to be engaged by, or be in sliding contact with, a tooth or projection 76 struck from the metal composing the handle 68. The curve of said face 75 is such that, in the passage 55 of the projection 76 there under, the latch is not moved.

The arcuate face 75 of the latch is formed, intermediate its length, with a semi-circular depression or notch 77. One edge of the 60 arcuate or cam face 75 has the beveled portion 78. The tip of the tooth or projection 76 of the operating handle has a semi-circular form and is normally adapted to be engaged by the notch 77 of the latch.

65 In a movement of the switch handle to

close the switch, the handle is moved rapidly toward the left, or switch closed position from the extreme right or open position. The toothed projection 76 of the handle in such movement moves under the 70 latch 73 without causing a movement thereof until it arrives at the gap or notch 77. The latch being now unsupported against downward movement, begins to fall. If the movement of the handle is sufficiently fast, the 75 projection 76 will move across the notch 77 before the latch falls sufficiently to effectively engage the projection, and the handle, therefore, is unrestrained in its movement into closed position. If the speed of operation of the handle, however, is below a certain predetermined value, the latch will fall sufficiently during the passage of the projection 76 across the notch 77 of the latch, to effectively engage the tooth and 80 thereby restrain the handle, and consequently the switch mechanism against further movement toward closed position.

A latch 80 is provided whereby the switch normally is restrained in closed position. 90 Said latch is formed, intermediate its length, with a boss through which a pin 80' extends, and upon which said latch is pivotally mounted. Said pin 80' is secured to the wall of the casing 11, and to a frame 81 secured to said casing and said latch is disposed therebetween.

The latch is formed with an end portion having a semi-circular roller engaging face 82, adapted to receive the roller 61 carried by the arm 60 of the switch mechanism to normally restrain said mechanism in closed position. That part of the latch beneath the circular recess 82 is reflexed to form an inclined portion 83 at right angles to the latch. Said inclined extension 83 is adapted to be engaged by the projection 71 formed on the handle in a movement of said handle toward full open position of the handle to move said latch from the switch mechanism and permit the movement of the switch members to open position.

100 A spring 84, coiled about the pin 80' tends to maintain the latch in normal raised and roller engaging position.

The latch extends beyond its pivoted connection with pin 80', and said extension is formed with a flange 85 disposed thereon at right angles to the plane of the latch. A spring 86 is coiled about the pin 80', and has one end 87 thereof extended under said flange. Said end 87 is upwardly bent and is pressed against the cover 18 in its closed position. The end 87 thereby forms means limiting the upward movement of the latch under the action of the latch spring 84. When the cover 18 is removed from the enclosure 11 the end 87 of the spring 86 is 110 no longer restrained in position, and there- 120 125 130

by tends to move upward because of its resiliency.

Due to the disposition of the flange 85 of the latch above said end 87, the upward movement of said end causes a movement of said latch to disengage the roller 61 of the switch mechanism, and thereby permits the switch members to move into open circuit position upon the removal of the cover.

The overload protective means for the switch include the current coils 88, which are disposed above the supporting base 10 within the enclosure of casing 11. The movable element of said coils are enclosed in the tubes 89, which project through the lower portion 12 of the enclosure 11 and terminate in the time limit means 90, which are of common construction.

Pins 91 are centrally and movably disposed within the solenoids and at the top portion thereof and project therethrough. Said pins are adapted to be engaged by the movable elements of said coils upon a predetermined current flow, and to be moved into engagement with a tripping frame, a component part of which is disposed above said solenoids and pins.

Said tripping frame is formed of a flat strip portion 92 extending above said pins, and adapted to be engaged thereby under certain conditions of current flow, and the ends of said strips are bent at right angles to form arms 93, which are pivoted at 80' and 94 to the casing 11. One of said arms 93 is disposed beneath the flange 85 of the latch 80, whereby in the upward movement of said tripping frame caused by the engagement therewith of the pins 91, said arm will engage said flange 85 to move said latch, and thereby cause its disengagement from the roller 61 of the switch operating mechanism, and thereby permit the movement of the movable switch member into open position.

The under-voltage release means include a coil 95 which is secured in a housing 96, disposed beneath the enclosure 11. A pin or rod 97 is secured to the movable element of said coil and projects upwardly through the bottom 12 of the enclosure 11 and the base 10, and is formed with an enlarged end or head portion 98. The rod 99 is pivoted in supports 100 secured to the base 11, and is formed with an end portion 101, which extends substantially at right angles from said straight rod, and encircles the stem 97 of under-voltage release coil. The other end portion 102 of said rod is bent in the reverse direction from the end 101, and a link 103 is pivoted thereto. Said link 103 is formed with a slot 104 at its upper end portion, and a pin 105 is disposed therethrough and secured to the latch 80. The slot 104 of said link provides means whereby the latch 80 may be moved

independently of said link to cause the opening of the switch. The enlarged head 98 of the rod 97, secured to the movable element of the no-voltage release coil, is normally maintained above and from contact with the end portion 101 of the rod 99 due to the energization of said coil.

If the energization of said coil is at any time insufficient to maintain the movable element thereof in elevated position, said element will descend, due to gravity, and move the enlarged head of the rod 97, thereof into engagement with end portion 101 of the rod 99, thereby transmitting through said rod and the link 103, a blow sufficient to move the latch 80 in an upward direction, and thereby cause the latch to become disengaged from the switch mechanism, which mechanism consequently is permitted to move to open circuit position.

The locking means whereby the cover 18 locks the oil receptacle 13 against unintentional removal from the switch housing, includes the vertical rod 106, which is slidably disposed in supports 107 secured to the enclosure or casing 11, and is normally pressed by a spring 108 against the cover 18. The lower end of said vertical rod is bent to form an end portion 109, which projects through the supporting base 10 and enclosure bottom 12 into the path of movement of one of the screw portions 14, and thereby restrains said oil receptacle against detachment.

When the cover 18 of said enclosure 11 is removed, the rod 106 is no longer maintained in depressed position, and therefore the rod moves vertically upward under the action of spring 108, which movement withdraws the end portion 109 away from the path of movement of a screw portion 14, and thereby permits the rotation of said oil receptacle for detachment from the switch housing.

I claim:—

1. In an oil switch, an enclosing casing, an oil receptacle, means removably securing said receptacle to said casing, a cover for said casing, and locking means controlled by said cover removably to lock said oil receptacle to said casing adapted to release the receptacle for subsequent removal from the casing.

2. In an oil switch, an enclosing casing, an oil receptacle removably secured thereto, a cover for said casing, a locking pin movable by said cover into locking position with said receptacle and a spring engaging said pin to move it from locking position upon removal of the cover from the casing.

3. In an oil switch, an enclosing casing, an oil receptacle rotatably removably engageable therewith, a cover for said casing, and a locking device normally held by said cover

- in a locking position in which it prevents rotation of said oil receptacle having means to move it from locking position upon moving the cover from the casing.
5. 4. In an oil switch, an enclosing casing, an oil receptacle removably secured thereto, a removable cover for said casing, a locking device for said oil receptacle normally held by said cover in locking position with 10 said oil receptacle and means associated with said locking device arranged to move it from locking position upon the removal of said cover, whereby said oil receptacle may be removed from said casing.
15. 5. In an oil switch, an enclosing casing, an oil receptacle rotatably removably engageable therewith, a removable cover for said casing, a locking pin extended within said casing downwardly beneath said cover and 20 engageable with said receptacle to prevent its removal, and a spring associated with said pin to withdraw it from engagement with said receptacle upon removal of said cover to permit the removal of the oil receptacle.
30. 6. In an electric switch, a supporting plate, two spaced-apart supporting members secured to and depending from said plate, two bars of insulating material secured to 35 said strips in spaced-apart relation, stationary switch members carried by one of said bars and movable switch members pivotally carried by said other bar.
35. 7. In an electric switch, stationary and movable switch elements, an insulating bar to which said stationary switch elements are secured, a separate insulating bar to which said movable switch elements are secured, a frame to which said insulating 40 bars are secured in spaced relation, a supporting base from which said frame depends, said stationary switch elements comprising flat strips secured to its insulating bar having its lower end portions reflected to form
- contact faces, and its upper portions extended through said supporting base for circuit connection, and switch operating mechanism supported above said base and extended therethrough for operative engagement with the movable switch elements. 45
50. 8. In an electric switch, a plurality of stationary and movable switch elements, a supporting base from which said switch elements depend, said movable switch elements comprising independent flat strips each 55 formed with a reflected end portion, auxiliary contacts slidably arranged in said end portions, brushes arranged on said flat strips intermediate the length thereof for contact with the stationary switch elements, the other end portions of said strips being twisted into a plane substantially at right angles to the plane of the body of the strip whereby said strips are pivotally connected to supports, a frame connecting said independent switch elements for unitary movement and switch operating mechanism connected with the ends of said connecting frame. 60
65. 9. In an electric switch a stationary switch element, and a cooperating movable switch element comprising a flat strip having its end portion reflexed to form a rearwardly directed portion substantially parallel with the body of the strip and spaced therefrom, an auxiliary contact slidably arranged in 70 said parallel end and body portions, a brush-member carried by the body portion, and said other end portion twisted at substantially right angles to the body portion to form a pivotal connection with a support. 75
80. In testimony whereof I have signed my name to this specification, in the presence of two subscribing witnesses.

GORDON CAMERON.
